UNITED STATES PATENT OFFICE.

FREDERICK CONRATH, OF ST. PAUL, MINNESOTA.

OIL-STOVE.

1,146,555.

Specification of Letters Patent. Patented July 13, 1915.

Original application filed December 9, 1908, Serial No. 466,639. Divided and this application filed December 20, 1909. Serial No. 534,077.

To all whom it may concern:

Be it known that I, FREDERICK CONRATH, of St. Paul, Ramsey county, Minnesota, have invented certain new and useful Improvements in Oil-Stoves, of which the following is a specification.

My invention relates to oil stoves or heaters, adapted for various purposes but designed particularly for use in freight cars 10 for shipping vegetables or fruit in cold weather, the object being to provide a stove which can be easily transported from place to place and provided with a chimney which will permit convenient access to the burner.

15 My invention consists generally in improved means for attaching the chimney to the stove.

In the accompanying drawings forming part of this specification, Figure 1 is a top 20 view of an oil stove embodying my invention, Fig. 2 is a similar view with the chimney tilted to allow access to the burner, Fig. 3 is a detail view of one of the hinges or pivots by means of which the chimney is 25 attached to the stove.

The subject matter of this application was included in my pending application filed December 9, 1908, Serial No. 466,639, and was divided out of that application.

30 In the drawing of this present case, 2 represents the stove containing the usual oil reservoir and provided with a burner 3.

40 4 is a chimney, preferably of metal and in the form of a frustum of a cone, though 35 any other shape may be employed if preferred as, for instance, the opposite walls may be parallel instead of tapered, so that the chimney or stack will be the same diameter at each end. The chimney is 45 secured by hinged devices arranged on each side thereof. Each of these hinge devices comprises an ear 5 secured to the lower wall of the chimney and having a loop 6 which cooperates with similar loops 7 on a plate 9 to form the straps or leaves of the hinge. Each hinge has a pivot pin 10 adapted to slip into the loops 6 and 7 when they are 50 arranged in alignment with one another and lock the ear and plate 9 of each hinge together. Each plate is preferably provided with a loop 11 adapted to receive a rod 12 which slides therein and is limited in its movement in one direction by a stop 13. Each pin 10 and the rod 11 of that hinge 55 is preferably formed from the end portions

of a piece of wire, the middle portion being curled to form a loop 14, which serves as a finger grip to move the pin and rod of each hinge from its locking to its releasing position. The rod 12 is longer than the pin 10 60 and allows the pin to be drawn out of the loops 7 a sufficient distance to release the loop 6 before the stop 13 contacts with the loop 11. With this construction I am able to disengage both sides of the chimney from 65 the stove or only one side, as desired. For convenience in carrying the stove I provide a bail 15 attached to the chimney by ears 16. The hinge connection of the chimney or stack with the stove allows the complete removal of the chimney from the stove or its separation from one side only to allow it to 70 be tilted on the other hinge or pivot to expose the burner, as shown in Fig. 2.

The carrying bail facilitates very materially the transportation of the stove from place to place, as from one box car to another. Oftentimes the bottom and sides of stoves of this kind become greasy through the presence of oil thereon or from coming 75 in contact with the floor of the car, and if it were necessary to carry the stove bodily in the arms it would be almost impossible to prevent the hands and clothing from becoming soiled. The use of the bail eliminates entirely all this annoyance incidental to an ordinary oil stove and permits it to 80 be picked up with one hand and transported. 85

I claim as my invention:

1. The combination, with a heater having 90 a burner, of a chimney having hinged connections therewith on each side of said burner, said hinged connections including loops mounted respectively on said heater and on said chimney and sliding hinge pins 95 passing through said loops, either one of said hinge pins being capable of withdrawal from its loops to allow the chimney to be tilted on the other pin and loops, said heater having guides thereon and said hinge pins 100 having members which are slidable in said guides and provided with stops for limiting the withdrawal of said hinged pins from said loops.

2. The combination, with a heater having 105 a burner, of a chimney having loops thereon, loops mounted on said heater and adapted to register with said chimney loops, guide loops mounted on said heater, pivot pins slidably mounted in said hinge loops and 110

also having shanks which are slidable in said guide loops and provided with stops for limiting their movement in said guide loops, said hinge pins and said guide shanks 5 being substantially parallel, the disengagement of a hinge pin from the chimney loop on one side allowing the chimney to be tilted on the hinge pin on the opposite side, said guide shanks preventing a complete

withdrawal of said hinge pins from said 10 loops.

In witness whereof, I have hereunto set my hand this 14th day of December 1909

FREDERICK CONRATH.
